TABLE OR THE LIKE

Norman Clayton Jenkins, 214 Thomas Ave.,
Nutter Fort, W. Va. 26301

Original design application Nov. 1, 1965, Ser. No. 87,971, now Patent 208,311, dated Aug. 15, 1967. Divided and this application July 26, 1967, Ser. No. 7,993

Term of patent 14 years

(Cl. D33—14)

The dominant features of my design reside in those portions shown in full lines on the drawing.

This application is a division of application Ser. No. 87,971, filed Nov. 1, 1965 and now Patent No. D.208,311.

I claim:

The ornamental design for a table or the like, substantially as shown and described.
